Norman Albert Whitaker, Belfast, Northern Ireland, assignor to The Tilley Lamp Company Limited, Belfast, Northern Ireland, a company of Great Britain

Filed July 29, 1964, Ser. No. 81,061

Term of patent 3½ years

(Cl. D81—10)

FIG. 1.

FIG. 2.

FIG. 3.

Des. 203,370

PAGE 2

FIG. 4.

FIGURE 1 is a front perspective view from above of the stove in a closed position.

FIGURE 2 is a rear perspective view from below of the stove in a closed position.

FIGURE 3 is a front elevation of the stove in a closed position.

FIGURE 4 is a front perspective view from above of the stove in an open position.

FIGURE 5 is a rear perspective view from above of the stove in an open position.

The interior of the stove in the conditions illustrated in FIGURES 4 and 5, is substantially open and unobstructed.

I claim:

The ornamental design for a portable cooking stove, substantially as shown and described.
